(57) **CLAIM**

The ornamental design for a golf club cavity, as shown and described.

DESCRIPTION

FIG. 1 is a heel side perspective view of our new golf club cavity;

FIG. 2 is a toe side perspective view thereof;

FIG. 3 is a bottom perspective view thereof;

FIG. 4 is a toe side view thereof; and,

FIG. 5 is a back side view thereof.

The portion of the golf club shown in phantom does not form any portion of the present invention.
